UNITED STATES PATENT OFFICE.

ARTHUR D. PRATT, OF SHORT HILLS, NEW JERSEY, ASSIGNOR TO THE BABCOCK & WILCOX COMPANY, OF BAYONNE, NEW JERSEY, A CORPORATION OF NEW JERSEY.

SUPERHEATER.

Application filed October 23, 1924. Serial No. 745,286.

My present invention relates to superheaters, particularly of the type in which the superheater is exposed to the radiant heat of the furnace.

5 My invention will be best understood from the following description, taken with the annexed drawing, in which Fig. 1 shows a boiler of the Stirling type embodying an illustrative form of my invention and Fig. 2 is a fragmentary view looking from the left of Fig. 1, the front wall being removed.

The boiler of the type illustrated comprises a mud drum 10 and steam and water drums 11, 12 and 13, the various steam and water drums connected to the mud drum by banks of inclined water tubes 15, 15^a and 15^b. It will be noted that the water tubes 15 connecting mud drum 10 and steam and water drum 11 are, for the most part, exposed to the radiant heat of the furnace, herein illustrated as comprising a grate 17. Among these tubes thus exposed to the radiant heat, I preferably locate a superheater which in the illustrated form, has headers 19 and 20 connected by tubes 21. Baffles 23, 24, 25 and 26 are provided to cause a proper flow of the gases over the entire set of boiler tubes. Preferably I locate the headers 19 and 20 back of the first baffle 23 and thereby protect them from the radiant heat of the furnace. Steam from the drum 13 is passed through the pipe 28 into the header 19 of the superheater and flows from the superheater at header 20.

As illustrated, I intersperse the tubes of the superheater, preferably regularly, among those of the boiler. In the specific form I have shown, the boiler tubes 15 in the front bank are widely spaced across the boiler, and two superheater tubes 21 inserted in each 40 of the spaces so formed. By this means the superheater tubes are partially surrounded by boiler tubes, every superheater tube being next and relatively close to at least one of the boiler tubes.

Superheaters located so as to receive radiant heat, are liable to be seriously damaged by the heat of the hot walls and of the furnace when steam is not being taken from the boiler as no steam is then flowing through the superheater. By my invention, I overcome this difficulty by arranging the superheater tubes so that each tube is partially surrounded by water tubes. Consequently, when steam is not passing through the superheater, overheating of the superheater will be minimized by the proximity of tubes containing water at a considerably lower temperature.

It will be understood that the specific arrangement I have shown is illustrative only and that various other arrangements of the superheater and boiler tubes can be made without departing from the spirit of my invention.

I claim:

1. In combination with a water tube boiler, having a plurality of water tubes exposed to the radiant heat of the furnace, a baffle behind said tubes, a superheater comprising headers located back of said baffle and tubes connecting said headers and extending in front of said baffle and entirely exposed on one side to the radiant heat of the furnace, said superheater tubes being spaced among said boiler tubes.

2. In combination with a boiler of the type comprising an upper and a lower drum connected by a plurality of inclined water tubes, said tubes being exposed to the radiant heat of the furnace, a baffle behind said tubes, a superheater comprising headers located back of said baffle and tubes connecting said headers and extending in front of said baffle and entirely exposed on one side to the radiant heat of the furnace, said superheater tubes being spaced among said boiler tubes.

ARTHUR D. PRATT.
